(57) **CLAIM**

The ornamental design for a container for cosmetic sponge applicator, as shown and described.

DESCRIPTION

FIG. 1 is a perspective view of a container for cosmetic sponge applicator showing the new design;

FIG. 2 is a front elevational view of the embodiment of FIG. 1 with the base portion attached to the cap portion;

FIG. 3 is a rear elevational view of the embodiment of FIG. 1 with the base portion attached to the cap portion;

FIG. 4 is a cross-sectional view of the container of FIG. 1 about line 4-4 with the base portion attached to the cap portion;

FIG. 5 is a front elevational view of the embodiment of FIG. 1 showing the cap portion;

FIG. 6 is a rear elevational view of the embodiment of FIG. 1 showing the cap portion;

FIG. 7 is a right side elevational view of the embodiment of FIG. 1 showing the cap portion;

FIG. 8 is a left side elevational view of the embodiment of FIG. 1 showing the cap portion;

FIG. 9 is a top plan view of the embodiment of FIG. 1 showing the cap portion; and,

FIG. 10 is a bottom plan view of the embodiment of FIG. 1 showing the cap portion.

Surface shading is used to shade FIGS. 1-10 to show clearly the character and contour of all surfaces of the 3-dimensional aspects of the design and form a part of the design sought to be protected. The broken lines illustrate portions of the container for cosmetic sponge applicator and form no part of the claimed design.
